Primary Examiner — Patricia A Palasik(74) *Attorney, Agent, or Firm* — Sughrue Mion, PLLC(57) **CLAIM**

The ornamental design for a can manufacturing apparatus, as shown and described.

DESCRIPTION

FIG. 1 is a perspective view from the front side of a can manufacturing apparatus.

FIG. 2 is a perspective view from the rear side thereof.

FIG. 3 is a front elevation view thereof.

FIG. 4 is a rear elevation view thereof.

FIG. 5 is a left side elevation view thereof.

FIG. 6 is a right side elevation view thereof; and,

FIG. 7 is a top plan view thereof.

1 Claim, 7 Drawing Sheets(56)
